UNITED STATES PATENT OFFICE.

WILLIAM E. PATZER, OF HASTINGS, NEBRASKA.

ICE-CREAM MEASURER AND DIPPER.

Application filed December 21, 1927. Serial No. 241,322.

This invention is a device for extracting measured quantities of ice cream from bulk and delivering the same in packages to retail customers. The object of the invention is to provide a simple, inexpensive and easily manipulated device whereby a desired quantity of ice cream may be withdrawn from a bulk supply and delivered as desired by a retail customer. The invention is illustrated in the accompanying drawing and will be hereinafter fully set forth.

In the drawing:

Figure 1 is a front elevation, partly broken away, of a device embodying the invention, and

Fig. 2 is a vertical longitudinal section of the same.

In carrying out the invention, there is provided a cylindrical body 1 having an open lower end and having its upper end closed by a cap or cover 2 through which are formed a plurality of openings 3 for the escape of any air which may be trapped under the cover in the operation of the device. Rising from the cover 2 is a standard 4 comprising spaced side members connected at their upper ends by a handle member 5 and reinforced at a convenient point in their height by a connecting web or brace 6, as shown. Near the lower ends of the side members 4, a transverse guiding yoke 7 is disposed between and rigidly connected with the side members, the said guiding element and the brace 6 being preferably formed integral with the side members. The members of the standard may also be formed integral with the cover 2 and the handle member 5 may likewise be formed integral with the standard thereby expediting the production of the device and reducing the cost. The guiding member 7 has a vertical opening 8 formed therethrough adjacent its front side and somewhat in advance of the side members of the standard while the inner portion of the guide between the side members of the standard has an opening 9 therethrough to receive the shank 10 of a plunger or ejector whereby the plunger will be held to a rectilinear path in its movement. The shank 10 is preferably flat-sided and passes through a correspondingly shaped slot 11 at the center of the cover 2 whereby twisting of the shank will be prevented and it will always be in operative relation to the ejecting element so that the measured ice cream may be discharged with certainty and ease.

The lower end of the shank 10 carries a disk 12 which is of proper diameter to fit closely but slidably within the cylinder 1 and on the back edge of the shank is a stop 13 adapted to impinge against the cover 2 to prevent the ejector dropping from the measuring body 1 in an obvious manner. On the front edge of the shank 10 are a series of ratchet teeth 14 which are adapted to be engaged by a pawl 15 pivoted to the lower end of a link 16 and pressed toward the shank by a spring 17 which has one end bearing upon the outer side of the pawl below the pivot 18 of the same and its other end secured in the link, as shown, and as will be understood. The link 16 passes freely through the opening 8 of the guide 7 and at its upper end is pivoted to a hand lever 19 which is fulcrumed, as at 20, between the side members 4 of the standard, the free end of the lever being normally held in its lowered position by a spring 21 bearing at its free end on the lever and having its other end secured to the handle member 5. It is to be noted that the pawl 15 is extended upwardly beyond its pivot 18 to provide a stop tooth 22 adapted to impinge against the under side of the guide yoke 7 when the link is in its raised position so that rocking of the pawl will be prevented and the pawl will consequently be held out of engagement with the teeth 14 on the shank 10. This action will be readily understood upon reference to Fig. 2 of the drawing.

The teeth 14 are spaced equi-distantly along the shank 10 and, if preferred, graduations may be marked along the shank adjacent the teeth to facilitate the reading of the device and insure accuracy in the measurement of the cream to be delivered. Normally the parts are in the position shown in the drawing with the piston or plunger disk 12 at the bottom of the cylinder 1. When a sale is to be made, the device is placed upon the bulk of ice cream so that the lower end of the cylinder 1 will rest on the ice cream and pressure is then exerted upon the handle 5 to force the cylinder into the ice cream. The pressure of the body of cream against the plunger disk 12 will cause the same to move relatively upward within the cylinder 1, and this movement may be arrested at any time by rocking the lever 19 upwardly toward the handle, whereupon the pawl 15 will at once ride into engagement with the tooth 14 presented thereto. The

continued opening movement of the ejector or plunger will thus be arrested and the device may be withdrawn from the body of ice cream, the portion of the ice cream which 5 may at that time be within the container withdrawing from the bulk of the commodity in a well known manner. The extracted ice cream may then be discharged into a receptacle or package provided therefor by 10 holding the device over the receptacle and exerting an increased pressure upon the lever 19 so that the link 16 will slide downwardly to the extent of movement of the lever and thereby cause the shank 10 and the ejecting 15 disk 12 to at once move downwardly within the container 1 and force out the ice cream in an obvious manner. Of course, it may be necessary to rock the lever two or more times to effect complete discharge depending 20 on the quantity of ice cream to be dispensed.

From the foregoing description, taken in connection with the accompanying drawing, it will be seen that I have provided an exceedingly simple device whereby ice cream 25 may be accurately measured so that a desired quantity may be quickly withdrawn from a bulk of the commodity and delivered to a customer. While the device is intended more particularly for use in the sale of ice 30 cream, it may be advantageously employed in retail sales of other commodities, such as butter and other articles which possess the quality of frictionally engaging the sides of a container so as to be retained therein until 35 pressure is exerted to effect ejection.

Having thus described the invention, I claim:

1. A dispensing device comprising an open bottom container, an ejecting disk slidably 40 mounted in the container, a shank rising from the disk through the top of the container and provided with graduated stops in one edge, a pressure element mounted above the container, a spring-pressed pawl 45 carried by said element and adapted to engage a selected stop on the shank, and means normally holding the pawl out of engagement with the shank.

2. A dispensing measure comprising an 50 open bottom container, an ejecting disk slidably mounted in the container, a shank rising

from the disk through the top of the container and provided with graduated stops on one edge, a pressure device mounted above the container, a pawl carried by the lower end of the pressure device and spring-pressed toward the shank to engage a selected stop thereon, a guide for the shank and said pressure device, and a tooth extending upwardly from the pawl and arranged to engage the under side of the guide whereby to normally hold the pawl out of engagement with the shank. 55

3. A measuring and dispensing device comprising an open bottom container, a plunger slidably mounted in the container, a shank rising from the plunger through the top of the container, a guide above the container slidably receiving the shank, a lever mounted above the guide, a link carried by the lever and extending through the guide, a pawl carried by the lower end of the link to engage the shank at a selected point in the length thereof, and an extension on the pawl adapted to impinge against 70 the under side of the guide whereby to hold the pawl normally out of engagement with the shank. 75

4. A measuring and dispensing device comprising an open bottom container, an ejector slidably mounted in the container, a shank rising from the ejector through the top of the container, a standard rising from the top of the container, a lever fulcrumed upon the standard near the upper end thereof, a link depending from one end of the lever, a spring connected to the standard and bearing against the opposite end of the lever to hold the link normally in raised position, and a pawl carried by the lower end of the link in position to engage the shank. 85

5. A measuring and dispensing device comprising an open-ended container, an ejector slidably mounted in the container and including a shank rising through the 90 top of the container, a standard rising from the top of the container, a lever fulcrumed on said standard, a link depending from the lever, and a pawl carried by the link and arranged to engage the shank. 95

In testimony whereof I affix my signature.

WILLIAM E. PATZER. [L.S.]
